LOCK FOR SAFES

Raymond A. Creswell, Los Angeles, Calif.

Application September 9, 1940, Serial No. 356,006

4 Claims. (Cl. 109—1)

This invention relates to an improved operating means for safe-locks.

Among the objects of the invention are to provide, for operating the lock of an office safe or container for valuables, a means manually accessible at a point located above the top of the safe, thereby making it possible for a person in an erect, standing position to operate the lock instead of being obliged to assume a kneeling or crouching posture in order to do so.

Another object of the invention is to provide an auxiliary indicating means and an operating device therefor, thus making it easier to observe that the proper turning movements are made in operating the lock.

Other objects, advantages and features of invention will hereinafter appear.

Referring to the accompanying drawing, which illustrates what is at present deemed to be a preferred embodiment of the invention.

Fig. 1 is a front view, slightly in perspective, of a safe equipped with the invention, the safe door being open.

Fig. 2 is a vertical section on a larger scale than Fig. 1, the safe being shown with the door closed and the plane of section being indicated by the line 2—2 on Fig. 1.

Fig. 3 is a front elevation of the safe, the door being closed.

Fig. 4 is a transverse section on line 4—4 of Fig. 2.

Fig. 5 is a transverse section on line 5—5 of Fig. 2.

On Figs. 4 and 5 the parts are shown in the positions they occupy when the door is open.

Referring in detail to the drawing, in Figs. 1 and 2 is shown a safe structure including a top wall 10 supported by upstanding side walls 11 in one of which is a spacious door opening 12 for which is provided a horizontally swingable door 13.

This safe is furnished with a lock operating means which includes a shaft 15 that projects through its top wall 10 and carries at its projecting end a pointer 16 which cooperates with a dial 17. A stepped opening 18 in said top wall 10 supports a bearing block 19 which, in turn, sustains the shaft 15 by means of the collar 20 fixed to said shaft. Said opening 18 is of a sufficient diameter to admit the shaft 15 together with a gear 21 fixed to its lower end.

The door 13, when closed, extends a considerable distance into the safe chamber 24. In its upper part said door (which is of a skeletal, filled in character) supports a bearing 25 which

underlies the hub portion 26 of a gear 27 fixed to the upper end of a shaft 28, said gear meshing with the gear 21 when the door is closed.

In a downwardly spaced relation to said bearing 25 said door also supports the bearing means 30 and 31 which respectively operatively engage the lower upstanding shaft 28 and support a horizontal shaft 32. Said shafts 28 and 32 respectively carry permanently intermeshing bevel gears 33 and 34. The door also carries in its inner lower portion a conventional combination lock 35 which is operable by said shaft 32.

To the outer end of shaft 32 is secured a crank 36 by which the set of extensible locking bars 38 are operable. The three shafts 15, 28 and 36 may be readily spoken of without confusion by respectively terming them the outer, inner and operating shafts.

A means is provided to maintain the gears 21 and 27 in proper relative rotational positions to each other, in conjunction with the timing means inside of the lock, so that the same teeth of the two gears will intermesh again whenever the door is brought back to its closed position, as were in mesh before it was opened. For this purpose, the upper shaft 15 and lower shaft 28 are each provided with a gear tooth centering means. This centering means for the upper shaft 15, includes a bent lever 40 which is mounted upon a bearing projection 22a carried by a cross wall or extension 22 in the upper part of the safe. Said lever 40 has a foot portion 40a which projects downwardly through an opening 22b in said cross wall. The upper part of said lever extends around to the front side of the shaft 15 and is there provided with a hook portion 41, the tip portion of which is sufficiently pointed to fit snugly within a narrow recess 42 in the shaft 15. A compression spring 43 is placed back of said lever and abuts a vertical portion 44 of the wall 22, and is held in place by lugs, as shown, to bear against said lever above the fulcrum normally to keep its tooth 41 in engagement with the recess of the shaft 15.

The gear tooth centering means for the lower shaft 28 includes a plunger 47 having a head 48 which works within a cylindrical part 49 of the inner wall 50 of the safe door. At the bottom of the cylindrical chamber 51, provided in the door wall, is a circular opening within which the plunger has a working fit. Within said chamber 51 a compression spring 52 is coiled around the plunger to cause its head to bear continually against the foot portion 40a of the lever 40. Like the lever 40, the front end of the plunger 47

is provided with a hook portion 53 and this hook portion is movable into and out of engagement with a recess 54 provided in the lower shaft 28 as a part of the gear tooth centering means therefor. The shaft 47 carries a stop collar 46 and has a squared portion 45 leftward of said collar to prevent rotation of the hook portion of the shaft.

In order to afford an indicating means observable from the front of the safe when the safe door is closed, said door is provided with an internal bearing projection 60 through which turnably extends a stub shaft 61 which carries at its inner end a bevel gear 62 in mesh with a bevel gear 63 fixed to the shaft 28. Said stub shaft 61 is furnished at its outer end with an indicating pointer 65 which cooperates with a graduated dial plate 66 attached to the face of the safe door.

In the operation of the device, when the parts are in the position shown in Fig. 2, the lower spring 52 overcomes the force of the upper spring 43 and therefore maintains the upper end of the gear tooth centering lever 41 in the disengaged position. The spring 43, being nearer to the fulcrum of the lever than the spring 52, acts less effectively upon the lever than does the latter spring but, when the door is closed, said spring 52 is compressed and the gear centering tooth 53 is disengaged from the intermediate shaft 28. Therefore it will be seen that the mechanism is operative by reason of the different operative force exerted upon the lever by said two springs.

I claim:

1. The combination, with a safe casing and a door of the skeletal type controlling a door opening in a side wall of said casing; of a vertical shaft in the top portion of said casing, bearing means for said shaft in said casing, cooperating indicator means carried by said casing and shaft and observable from a point above the safe to indicate the rotational positions of said shaft, a gear carried by the lower end portion of said shaft within the space included within the door opening, a lower vertical shaft mounted upon the door, said lower shaft projecting upwardly above the part of the door upon which it is mounted, a gear fixed to the upwardly projecting portion of said lower shaft, this gear being in mesh with the first recited gear when the door is in its closed position, means carried by the door to indicate the rotational position of said lower shaft, this means including a dial and pointer carried by the outer face of the door, a gear tooth centering means carried by the casing and operatively related to said upper shaft, a gear tooth centering means carried by said door and operatively related to said lower shaft, both of said centering means furnished with spring controls whereby they are automatically moved into engagement with the shafts to which they are operatively related when the door is opened, a tumbler lock assembly, means operatively connecting said lock assembly with said lower shaft, and means for operating the door bolts, the latter means being operatively related both to said lower shaft and said locking assembly.

2. In a safe of the type described, the combination with the casing having a door opening in its side and a skeletal door movable to and from a closed position in relation to said opening; of a conventional tumbler lock assembly carried by said door to control the operation of

its locking bars, a shaft carried by said door and rotatable from the exterior thereof to operate said lock assembly, an intermediate shaft and gear assembly operatively related to the first recited shaft and furnished with rotation indicating means observable in front of the safe when the door is closed, an upper shaft in a geared relation to said intermediate shaft, said upper shaft being furnished with rotational indicating means on the top wall of the casing, and gear tooth centering means for both said upper shaft and said intermediate shaft, said centering means both automatically moving to operative positions when the door is open and to inoperative positions when the door is closed.

3. The combination, with a safe casing having a side wall with a door opening and a door movable to and from a closed position in relation to said opening; of an outer shaft rotatably mounted upon said casing and furnished with indicating means to indicate its rotational position, an inner shaft carried by said door, the latter shaft being in a geared relation to the former shaft when the door is closed and in an inoperative relation thereto when the door is open, a lever pivotally mounted upon said casing, said lever having a tooth portion engageable with a notch in said outer shaft to hold said shaft in a gear tooth centering position, a spring tending to hold said lever in engagement with said notch, a plunger slidably mounted upon said door and having a toothed portion seated in a notch in said inner shaft when the door is open, said plunger being brought into an engaging relation to said lever when the door is closed, whereby said lever is at such time disengaged from said outer shaft, and said plunger by reason of its engagement with said lever is simultaneously disengaged from said shaft, a spring tending to hold said plunger in engagement with the notch of said inner shaft, said spring having a force cooperative with the first recited spring, indicator means carried by the door for said inner shaft to indicate its rotational position, gearing whereby said indicator means is at all times operatively related to said inner shaft, a conventional lock assembly operatively related to said inner shaft, and manually operable means to control said locking assembly operatively related to said inner shaft to rotate the latter.

4. In a safe of the type described, the combination, with the casing having a door opening in its side and a door movable to and from a closed position in relation to said opening; of a conventional lock assembly carried by said door to control the operation of its locking members, a shaft carried by said door and rotatable from the exterior thereof to operate said lock assembly, an intermediate shaft and gear assembly carried by the door operatively related to the first recited shaft and furnished with rotation indicating means observable in front of the safe when the door is closed, a third shaft having bearings within the body portion of the safe and extending to the exterior thereof where it is furnished with rotation indicating means, separable gear means interlocking the intermediate and third shaft, and gear tooth centering means for both the last recited shafts, said centering means both automatically moving to disengaged positions when the door is closed and to engaged positions when the door is open.
